THOMAS H. SYMINGTON AND PERY R. DRENNING, OF BALTIMORE, MARYLAND, ASSIGNEES, BY MESNE ASSIGNMENTS, TO T. H. SYMINGTON AND SON, INC., OF BALTIMORE, MARYLAND, A CORPORATION OF MARYLAND.

TRUCK BOLSTER WITH ABSORPTION MECHANISM.

Application filed October 7, 1926. Serial No. 140,181.

The invention relates to truck bolsters for use in connection with railway car trucks.

The principal object of the invention, generally stated, is to provide a novel shock absorbing mechanism within each end portion 5 of a truck bolster, the shock absorbing mechanism embodying resilient means co-operating with and acting in series with respect to whatever spring supporting means 10 may be provided for the bolster.

An important object of the invention is to provide a bolster equipped internally with a combination of resilient and friction means acting in conjunction and in series with the 15 truck springs, the entire mechanism increasing the spring capacity and avoiding overloads on the truck springs.

One of the objects of the invention is to provide a bolster with an internal resilient 20 means having considerable travel, which travel acts in series with the bolster supporting spring. By providing increased travel trucks will negotiate out of surface track with greater safety.

A still more specific object of the invention is to provide a bolster with an internally located cushion and friction mechanism embodying coacting wedge elements 25 operating in conjunction with springs, the combined action absorbing shocks and jars 30 and increasing the capacity of the truck springs.

Still another object is the provision of a bolster in which means is provided for maintaining the wedge elements in place prior to 35 installation within the truck so that dislocation or loss of any of the parts in handling will be avoided.

An additional object of the invention is to 40 provide a bolster which, though equipped with the shock absorbing means or increased capacity producing means, may be used to replace any of the standard types of bolsters, no changes in the construction of the 45 side frames or other elements being necessary.

A further object of the invention is the provision of a mechanism of this character 50 which will be simple and inexpensive to manufacture, easy to install, positive in action, efficient and durable in service, and a general improvement in the art.

With the above and other objects and ad-

vantages in view, the invention consists in the details of construction and arrangement of parts to be hereinafter more fully described and claimed, and illustrated in the accompanying drawing in which:

Figure 1 is a longitudinal vertical section through one end of a truck bolster embodying the invention, and

Figure 2 is a cross section taken on the line 2—2 of Figure 1.

Referring more particularly to the drawings, the numeral 1 designates the body of the bolster which is of the usual hollow formation and which may have any desired specific shape. This bolster is provided centrally of its top with the usual center bearing 2 beneath which there are preferably 70 provided vertically extending reinforcement webs 3 located at opposite sides of the vertical axis, only one web being, however, illustrated. The major portion of the bottom of the bolster 4 is represented as closed and each end 5 is open at its bottom and otherwise formed to define a pocket 6, the outer end wall 7 of which is closed except for a hole 8 therein. At some intermediate point in its interior the bolster is formed or provided with a guide 9 which is preferably 75 formed integrally with the bolster and supported or strengthened by webs 10.

Of course the ends 5 of the bolster are intended to extend into or be located within 85 the window openings of truck side frames and to be supported by whatever spring devices may be provided for the purpose. It is of course not intended that the bolster itself be supported upon the truck springs as the 90 present invention provides interposed means which will act to absorb shocks and vibration and which will also act to increase the spring capacity and travel. This shock absorbing means preferably comprises an elongated rod 11 mounted within each end portion of the bolster and slidable through the guide 9. Secured to the outer end of each rod, as by a key 12 or the like is a wedge member 13 having a hub portion 14 through 100 which the key 12 passes, the ends of the key being flush with or sunk below the outer surface of the hub portion so as not to interfere with movement thereof inasmuch as the hub portion is slidable through the hole 8. 105 However, a plurality of rods with the same

wedges may be used. The upper surface of the wedge member 13 is horizontal and rests against the flat underside of the top of the end portion of the bolster. The face 15 of the wedge member nearest the center of the bolster is inclined downwardly and outwardly as clearly illustrated.

The shock absorbing mechanism further includes a wedge member 16 within each pocket inwardly of the wedge member 13 and formed preferably as a counterpart thereof. The wedge member 16 is similarly formed or provided with a hub portion 17 which abuts against a collar 18 slidable on the rod 11 in engagement with one end of a coil 19 which surrounds the rod and which has its other end abutting against the guide 9. The inner end of each rod 11 carries a collar 20 abutting against one end of a coil spring 21 arranged in surrounding relation to the rod 11 and abutting against the member 9. For facilitating assembling of the parts, it is preferable that the inner end of each rod 11 be threaded and provided with a nut 22 which bears against the collar 20. The top surface of the wedge member 16 is horizontal and bears flat against the inside of the bolster, whereas the outer surface 23 is inclined oppositely to the inclination of the surface 15 of the opposed wedge member 13.

Located within the bottom portion of each pocket 6 of the bolster is a combined spring seat and wedge member designated generally by the numeral 24 which is intended for vertical movement and which has its bottom 25 adapted to rest upon the truck springs indicated diagrammatically at 26. The member 24 has an upstanding wedge portion 27 recessed or otherwise formed at 28 to straddle the rod 11. This wedge portion 27 is located between the wedge members 13 and 16 and has inclined sides 29 and 30 cooperating with the inclined surfaces 15 and 23 of the wedge members 13 and 16, respectively.

When the structure is assembled within the bolster it is intended that the springs 19 and 21 be placed under initial compression, the exact degree being a matter to be determined by experiment or computation and depending upon the nature of the car, the load to be sustained, etc. To hold the parts in assembled relation especially prior to the installation of the bolster within a truck, we preferably provide suitable securing means such as the bolts indicated at 31, which bolts are passed through suitable holes 32 in the top of the member 27 and screwed into suitable tapped holes 33 in the top 5 of the bolster. To facilitate casting of the member 27 and at the same time to provide means whereby access may be had to the bolts 31, the bottom 25 of the member 27 is preferably formed with hand holes 34. After the device is assembled within a bolster, it is of

course clear that the bolster is installed with a truck in the usual manner.

In the operation, it will be seen that the coil springs 19 and 21 are in series with the truck springs 26, as are also the various wedge members 13, 16 and 27. The position of the parts illustrated in the drawings is that which they will occupy under preliminary or light load conditions. Clearly, when additional load is imposed upon the bolster, the member 24 will move upwardly with respect to the bolster, the inclined sides 29 and 30 thereof in engagement with the inclined surfaces 15 and 23 of the wedge members 13 and 16 acting to force the members 13 and 16 apart longitudinally of the bolster and against the resistance of the springs 19 and 21. Owing to the frictional engagement of the surfaces 15 and 29, 23 and 30, and the top surfaces of the wedge members with the underside of the top of the bolster, it is clear that the action of the springs 19 and 21 will not be abrupt, the movement under all conditions being gradual. Obviously this will act to absorb shocks and jars incident to car travel. Furthermore, the springs 19 and 21, being in series with the truck springs, will operate to give greatly increased spring capacity so that overloading of the truck springs, with resultant disadvantages, will be entirely avoided.

From the foregoing description and a study of the drawing it will be apparent that the spring capacity and travel of the truck springs will be increased and that the action will be smoothed out and joggle eliminated. Furthermore, as the coil springs within the bolster have a different period of vibration from the truck springs it is evident that synchronization will be broken up, thus checking any tendency of the car to develop roll or side sway. It is really believed that the construction, operation and advantages will be readily apparent to one skilled in the art without further explanation.

While we have shown and described the preferred embodiment of the invention, it will be understood that the disclosure is merely an exemplification of the principles involved and it should be understood that we reserve the right to make such changes in the details of construction as well as the arrangement and combination of parts to increase the adaptability and widen the field of utility of the device, provided such modifications or variations do not depart from the salient features of the invention or the scope of the claims hereunto appended.

Having thus described the invention, we claim:

1. In a railway truck bolster, a vertically movable member within each end thereof adapted to seat upon the truck springs and having a vertically movable wedge portion thereon, other wedge members coacting with

said wedge member and movable thereby, and spring means opposing movement of said second named wedge members.

2. A railway truck bolster provided with 5 in each end with shock absorbing means including a vertically movable member adapted to seat upon the truck springs and formed with a wedge portion, a pair of wedge members arranged longitudinally of the bolster 10 and engaging against opposite sides of said wedge portion, and a plurality of coil springs operatively connected with the wedge members for opposing separating movement thereof.

15 3. A railway truck bolster having each end formed with a pocket open at its bottom, a member mounted within each pocket for vertical movement and adapted to seat upon the truck springs, said member including a 20 wedge portion, a longitudinally extending rod within each end of the bolster and slideable in a longitudinal direction, wedge members carried by each rod and disposed against opposite sides of said wedge portion, and spring means urging said wedge members toward each other.

4. A railway truck bolster provided at each end with a pocket having an open bottom, a member located within each pocket 30 for vertical movement therein, said member being adapted to seat upon the truck springs and having a wedge portion, a rod extending longitudinally within each end portion of the bolster and slideable longitudinally thereof, a wedge member secured upon the outer end of each rod and engaging against the outer side of said wedge portion, a wedge member slideably mounted upon each rod and engaging against the inner face of said 35 wedge portion, and spring means urging said wedge members toward each other.

40 5. A railway truck bolster provided at each end with a pocket having an open bottom, a member located within each pocket for vertical movement therein, said members being adapted to seat upon the truck springs and each having a wedge portion, a rod extending longitudinally within each end portion of the bolster and slideable longitudinally thereof, a wedge member secured upon the outer end of each rod and engaging against the outer side of said wedge portion, a wedge member slideably mounted upon each 45 rod and engaging against the inner face of said wedge portion, and coil springs surrounding said rods and operatively connected with the wedge members for opposing separating movement thereof.

60 6. A railway truck bolster provided at each end with a pocket having an open bottom, a member located within each pocket for vertical movement therein, said members being adapted to seat upon the truck springs, 65 each of said members having an interme-

diate wedge portion thereon, a rod extending longitudinally within each end portion of the bolster and slideable longitudinally thereof, a wedge member secured upon the outer end of each rod and engaging against the outer side of the first named wedge member, a wedge member slideably mounted upon each rod and engaging against the inner face of the first named wedge member, a combined guide and abutment member within 70 the bolster and through which each rod is slideable, a pair of coil springs encircling each rod and abutting against the guide, a collar secured upon the inner end of each rod and bearing against the end of the innermost spring, and a collar slideable upon each rod and engaged by the inner end of each of the last named wedge members.

7. In a truck bolster, the combination of 75 an upwardly movable member mounted within each end thereof and adapted to seat upon the truck springs, said member having a wedge portion, and spring pressed wedge means engaging said wedge portion and extending longitudinally of the bolster.

8. In a truck bolster, the combination of 80 pockets in the ends thereof, upwardly movable members mounted within said pockets and adapted to seat upon the truck springs, and combined cushion and friction producing means movable longitudinally of the bolster within each end thereof for opposing upward movement of said members.

9. A truck bolster having each end formed 85 with a pocket with an open bottom, wedge members located within each pocket and removable toward or from each other, spring means operating longitudinally of the bolster for opposing separating movement of the wedge members, and a vertically movable 90 combined spring seat and wedge member cooperating with and located between said first named wedge members for moving the same apart against the resistance of the springs upon upward movement of the follower with 95 respect to the bolster.

10. In a truck bolster, absorption mechanism therein including wedge means embodying a vertically movable wedge member adapted to seat upon the truck springs.

11. In a truck bolster, the combination of 100 an upwardly movable wedge member mounted within each end thereof and adapted to seat upon the truck springs, and wedge means within the bolster cooperating with 105 said wedge member.

12. In a truck bolster, absorption mechanism including an upwardly movable member mounted within each end of the bolster and adapted to seat upon the truck springs, 110 said member having a wedge portion, and spring-pressed wedge means within the bolster coacting with said wedge portion.

13. In a truck bolster, the combination of 115 a substantially vertically movable wedge

member within each end thereof adapted to seat upon the truck springs, other wedge members coacting with said wedge member, and combined guide and supporting means for the second named wedge members extending longitudinally of the bolster.

14. In a railway truck bolster, a vertically movable wedge member within each end thereof adapted to seat upon the truck springs, a wedge member above and coacting with said wedge member and movable thereby, spring means opposing movement of said second named wedge member, and means for limiting the movement of the first named wedge member downwardly with respect to the bolster.

15. In a railway truck bolster, a vertically movable wedge member within each end thereof adapted to seat upon the truck springs, a wedge member above and coacting with said wedge member and movable within the bolster, and means engaging the first named wedge member and the bolster for limiting downward movement of the former with respect to the latter.

16. In a railway truck bolster, a vertically movable wedge member within each end thereof adapted to seat upon the truck springs, a horizontally movable wedge member above and coacting with said first named wedge member, spring means opposing movement of the second named wedge member, and means connecting the first named

wedge member with the bolster for preventing separation.

17. In a railway truck bolster, a vertically movable wedge member within each end thereof adapted to seat upon the truck springs, a horizontally movable wedge member above and coacting with said first named wedge member, spring means opposing movement of the second named wedge member, and means connecting the first named wedge member with the bolster for preventing separation, said means being fixed with respect to the bolster and slidable with respect to the first named wedge member.

18. In a railway truck bolster, a vertically movable wedge member within each end thereof adapted to seat upon the truck springs, a horizontally movable wedge member above and coacting with said first named wedge member, spring means opposing movement of the second named wedge member, and means connecting the first named wedge member with the bolster for preventing separation, said means comprising a securing member extending through the bolster and the first named wedge member, the first named wedge member being slidable with respect to said securing element.

In testimony whereof we affix our signatures.

THOMAS H. SYMINGTON.
PERCY R. DRENNING.
